UNITED STATES PATENT OFFICE.

MAURICE J. WOHL, OF NEW YORK, AND HARRY HERTZBERG, OF BROOKLYN, NEW YORK, ASSIGNORS TO ABBOT A. LOW, OF HORSESHOE, NEW YORK, MAURICE J. WOHL, OF NEW YORK, N. Y., AND HARRY HERTZBERG, OF BROOKLYN, NEW YORK, TRUSTEES.

ELECTRICALLY-OPERATED MEANS FOR PRODUCING MECHANICAL MOVEMENTS.

952,778.

Specification of Letters Patent. Patented Mar. 22, 1910.

Application filed March 20, 1908. Serial No. 422,274.

To all whom it may concern:

Be it known that we, MAURICE J. WOHL and HARRY HERTZBERG, citizens of the United States, and residents, respectively, of the 5 city of New York, borough of Manhattan, county and State of New York, and of the city of New York, borough of Brooklyn, county of Kings, and State of New York, have invented certain new and useful Im- 10 provements in Electrically-Operated Means for Producing Mechanical Movement, of which the following is a specification.

This invention relates to mechanical movements, and the object is to produce unidirectional rotary movement through the expansion and contraction of electrically-heated wires.

Broadly, the invention consists in a thermal expandable wire, means for heating said wire electrically, a rotary driven member, and driving connection between said wire and said driven member whereby the linear movement of the wire is converted into unidirectional rotary movement.

25 While the invention may be presented in a variety of forms, the preferred embodiment is one in which there is a driven rotary member, an oscillatory member, driving connection between said members adapted to 30 convert the movement of said oscillatory member into unidirectional rotary movement in the driven member, and an electrically heated wire, or wires whose contraction and expansion actuate said oscillatory mem- 35 ber.

One application of the broad features of this invention, namely, the utilization of a pair of thermal members extending in opposite directions from an oscillatory member 40 which is arranged to be actuated thereby, is shown and claimed in our co-pending application for an electrical measuring instrument filed March 20, 1908 under Serial No. 422,275.

45 Referring to the drawing, which shows a semi-diagrammatic view of one embodiment of the invention, 1 indicates an electrical circuit, 2 a source of current therein, and 3 any suitable base or support on which the 50 several parts to be described may be mounted.

4 indicates the driven member, which may be in the nature of a ratchet wheel, as shown.

5 is the oscillatory member, which may be of various constructions, and variously associated with the driven member 4, but here shown as a lever, pivoted intermediate its length, as at 6, and carrying at one end a spring held, pivoted pawl 7, which engages with the teeth of the ratchet wheel 4. Connected to said lever 5 are one or more expandable wires 8. These are preferably secured tangentially in couples to an insulating hub 9 on the lever 5, the members of each couple being connected to points on opposite sides of the hub. The outer ends of the members of each couple are connected to opposed spring supports 10 by tension adjusting devices 11. While the heating and consequent expansion of the wires may be effected in various ways, we prefer to accomplish the result by connecting them in series in the circuit 1. In order to prevent the expansion or contraction of either of the couples under changes in temperature, 75 due to causes other than the heating effect of the electric current, affecting the lever 5 each pair of supports 10 is connected by a compensating wire 12, connected to the supports by tension adjusting devices 13. Each 80 wire 12 is adapted to have the same total linear expansion per unit change in surrounding temperature as the corresponding couple 8; whereby mere changes in atmospheric temperature result only in the wires 85 12 changing the flexure of the supports 10. Since the total change of flexure of each pair of supports 10 exactly equals the total change in length of the couple 8, under such 90 conditions, it is obvious that the outer ends of the wires 8 suffer displacement, but that their inner ends, connected to the hub 9, do not. An adjustable weight 14 moves lever 5 on expansion of wires 8.

95 Preferably, the circuit is made and broken automatically. While this may be accomplished in a variety of ways, the following is an operative construction: 15 is a stationary contact in the circuit, and 16 a contact in the form of a lever of the first order. 100 The rear end of contact 16 is positioned to be engaged by spaced projections 17 on the adjacent end of the lever 5. A spring 18 engages with a V-shaped shoulder 19 on the lever-contact 16, in such fashion that, when 105 the contact 16 passes dead center in either

direction, the resiliency of the spring forces it rapidly to the limit of movement in that direction. Stops 20 may be employed to limit the movement of the contact 16. When 5 contact 16 is at the limit of movement in one direction, it rests upon contact 15; when at the limit of movement in the other direction, the circuit is broken.

The operation is as follows: Assuming the 10 circuit to be closed, the current passes through the wires 8, which, being in the nature of resistance wires, are heated and expanded. This permits the weight 14 to tilt the lever 5, carrying the pawl 7 upward, 15 inoperatively, over the teeth of the ratchet wheel 4. A pawl 21 may be provided for preventing retrograde movement of the wheel 4 during this action. During this movement of the lever 5, the upper projection 17 20 has engaged the rear end of the pivoted contact 16, moving the outer end of the latter upward, until the dead center is passed, when the spring 18 quickly forces the contact 16 to the limit of movement, thus breaking 25 the circuit. The wires 8 now cool and contract, turning the lever 5 in the opposite direction against the force of the weight. The results are two-fold: First, the pawl 7 rotates the wheel 4 in the direction of the 30 arrow, and, second, the lower projection 17 engages with the contact 16, with the result that this contact is shifted to close the circuit again. The former operation is now repeated, and the cycle of operations continued as long as there is current. A circuit breaker 25 may be inserted in the circuit 35 for manually interrupting the current.

While we have described one embodiment of our invention with some particularity, it 40 will be readily understood that the construction may be greatly varied without departing from the invention as defined in the following claims.

What we claim as new is:

45 1. A mechanical movement, comprising a driven rotary member, an oscillatory member, driving connection between said members adapted to convert the movement of said oscillatory member into unidirectional 50 rotary movement in the driven member, a pair of thermal expansible wires extending in opposite directions under tension connected at their inner ends to said oscillatory member at points at opposite sides of the 55 pivotal axis thereof, supports to which the outer ends of said wires are connected, and means for electrically heating said wires simultaneously.

2. A mechanical movement, comprising a 60 driven rotary member, an oscillatory mem-

ber, driving connection between said members adapted to convert the movement of said oscillatory member into unidirectional rotary movement in the driven member, a pair of thermal expansible wires under tension connected at their inner ends to said oscillatory member at points at opposite sides of the pivotal axis thereof, spring supports to which the outer ends of said wires are connected, means for electrically heating 70 said wires, and a compensating wire, substantially as described, stretched between said supports.

3. A mechanical movement, comprising a driven rotary member, an oscillatory member, means for driving said rotary member from said oscillatory member, a plurality of pairs of thermal expansible members operatively connected to said oscillatory member, the thermal members of each pair extending in opposite directions, and means for simultaneously and intermittently heating 75 said thermal members.

4. A mechanical movement, comprising a driven rotary member, an oscillatory member, means for transmitting the movement of said oscillatory member to said rotary member, a plurality of thermal expansible members arranged in pairs in which the direction of pull is in opposite directions, 80 each pair being operatively connected to said oscillatory member and electrically connected to operate simultaneously to actuate said oscillatory member, and means for passing a heating current simultaneously and 85 intermittently through said thermal members.

5. A mechanical movement, comprising a driven rotary member, an oscillatory member, means for driving said rotary member from said oscillatory member, a plurality of 100 pairs of thermal expansible members under tension connected at their inner ends to said oscillatory member and at their outer ends to spring supports, spring supports positioned at the outer ends of said thermal 105 members, a plurality of compensating thermal members each operating in conjunction with one of said pairs of thermal members and extending between said spring supports, and means for intermittently heating 110 said thermal members.

Signed at New York, in the county of Kings and State of New York, this 18th day of March 1908.

MAURICE J. WOHL.
HARRY HERTZBERG.
